(57) **CLAIM**

The ornamental design for an emergency rollup blind for a door's window, as shown and described.

DESCRIPTION

FIG. 1 is a rear perspective view of an emergency rollup blind for a door's window showing my new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof;

FIG. 7 is a bottom view thereof; and,

FIG. 8 is a front perspective view thereof shown in a rolled up position.

The broken lines shown in FIGS. 1, 2, 3, and 8 depict stitching.
